SAMPLING APPARATUS

Jan Visman, Brunssum, Netherlands, assignor to
De Directie van de Staatsmijnen in Limburg,
Heerlen, Netherlands

Application October 3, 1950, Serial No. 188,159
In the Netherlands October 12, 1949

7 Claims. (Cl. 73—424)

1

The present invention relates to an apparatus for sampling a small quantity of material which is representative of the average of some large amount, and more particularly to apparatus for mechanically obtaining sample quantities of heterogeneous granular material, such as coal, ores and the like, from a bulk of such material as it is moved or transported past a sampling station.

Heterogeneous granular materials are composed of small lumps or particles differing in diameter and composition, and examples of such materials are coal with a low ash content, or a high grade ore with valueless gangue. In order to examine the properties of heterogeneous granular materials to determine their composition, it is a common practice to take samples therefrom and to analyze the samples.

Sampling usually consists of taking portions or cuts periodically from a stream of material as it moves or is being transported past a sampling station. A number of these samples obtained from the different parts of the bulk material are combined to form a "gross sample." Contents of the gross sample are thoroughly mixed and usually after crushing, a sample is taken therefrom of a size customary for analyzing.

The different sizes of granules of the heterogeneous material to be sampled tend to segregate when the material is being transported on a belt-type conveyor or when it is dropped from the delivery end of such conveyor or when dropping from an inclined conveying trough or pipe. The larger lumps or particles will move relative to the smaller ones.

Presumably, on account of this segregation, well known automatic samplers such as the "guillotine coal sampler" (vide Colliery Engineering, volume 22, page 117 (1945)) and "Gröppel Probenehmer" (vide Glückauf, 1935, page 705) have been designed to cut portions or samples periodically from a passing stream of material by intermittent transverse movements across the stream. The width of these cuts depends on the width of the sample cutter, which cuts across the entire width of the stream of material to be sampled.

Thus the size of every sample will be comparatively large if the stream of material is wide, as is usually the case with products transported in bulk. The gross sample, consisting of a combined number of samples taken periodically, consequently will be undesirably large and therefore difficulties are encountered and errors occur in reducing such a large quantity into a fair

sample of the size customarily used for analysis. The greater accuracy which might be expected to result from a large total sample is not attained. In the past, it has been a practice to take samples of comparatively large size and in the case of coal, the incremental weights of the samples have been specified to range from $\frac{1}{2}$ to 2 kg. This range, which has been accepted in the past, is obtained from the ratio between the weight of the separate sample increments and the particle size of the particular material to be sampled. The weight of the sample (expressed in lbs), should be at least equal to two or three times the diameter (measured in inches) of the coarsest particles as suggested in the British Standard Institution No. 735-1944, page 9, table 1a, and the A. S. T. M. Standards on Coal and Coke, September 1948, page 4, table II. Contrary to this established concept, I have shown and published in the Trans World Power Conference 1947, volume II, pages 430-441 that a higher sampling accuracy can be obtained by taking a larger number of individual samples of smaller size. In addition, I have discovered that it is unnecessary for the weight of a sample to be more than a few times the individual weight of the coarsest particles in the bulk material. I have also found that it is unnecessary for a sample to comprise a complete cut across the stream of material in that it may be a small fraction of such a cut provided a sufficiently large number of such small samples are collected. By taking a large number of small samples, a sample can be obtained that is thoroughly representative of the average of the entire stream of material.

Therefore, an object of the invention is to provide a sampling apparatus which will take up the particles constituting the sample from substantially the interior of the stream of material. A more accurate representation is obtained by taking a sample from the interior of the stream since the chances of segregation of the heterogeneous granular material are relatively great at the surface of the stream. A further object of the invention is to provide a simple, compact, practical and reliable sampling apparatus by means of which a sample of relatively small size may be taken up at regular intervals from the stream of material as it moves or is transported past the sampling apparatus. A still further object of the invention is to provide an apparatus for taking a sample where the minimum weight of the sample will only be a few times the individual weight of the coarsest particles present in the heterogeneous material.

These and other objects of the invention will appear more clearly from the specification, claims, and accompanying drawings in which:

Figure 1 is a front elevation of the sampling apparatus mounted over a belt conveyor.

Figure 1a is a sectional view on the line I—I of Figure 1.

Figure 1b is a sectional view on the line II—II of Figure 1.

Figure 2a is an enlarged longitudinal cross-sectional view of the sampler tube.

Figure 2b is an enlarged longitudinal cross-sectional view of a modified form of the sample tube.

Figure 3a is a plan view from beneath the sample tube of Figure 2a.

Figure 3b is a plan view from beneath the modified sample tube of Figure 2b.

Referring to the drawings, wherein like character or reference numerals represent like or similar parts, the sampling apparatus comprises a hollow discharge tube 2 having a detachable tapered sample collecting tube or nozzle 3, connected in axial alignment therewith. One or more discharge tubes 2 and the sample collecting tubes 3 are mounted for rotation on a horizontal shaft 1 located transversely over a belt conveyor 9 or the like. Any suitable means may be used to attach the discharge tube 2 to the rotatable horizontal shaft 1, and as best shown in Fig. 1a and 1b the tube 2 may be welded to a rectangular shank portion of the shaft 1. As noted in Figure 1, the plane of rotation of the discharge and sample collecting tubes is on an incline from the vertical so that the sample collecting tube 3 can be swung through the material to be sampled in an arcuate path, opposite the direction of movement of the stream of material to be sampled.

Horizontal shaft 1 is supported over the belt conveyor 9 by means of the bearing 14 and a motor which is also used to drive it. Casing 10, which houses the motor, also houses a time relay and a circuit breaker 4, so that the shaft 1 and the sample collecting and discharge tubes may be intermittently rotated at predetermined intervals. It is obvious that the intervals for rotating the sample collecting tube 3 may be varied, depending on the material to be sampled. As an example, the apparatus can operate to take 15 samples per minute. With a stream of material moving at a speed of 2 m./sec. and conveying 200 ton/h., the sample collecting tube may be operated to take samples averaging 1 to 2 ozs., with a maximum particle size being 8 mm.

Referring specifically to Figures 2a and 3a, the sample collecting tube 3 is connected to the discharge tube 2 by means of a flange 16 and a screw bolt 17. Sample collecting tube 3 which tapers from a flange 16 to an end closure wall 13, has a nose-like projection 12 adjacent to the end closure wall 13. Nose-like projection 12 is formed by bending the wall of the sample collecting tube 3 outwardly so as to produce a local radial enlargement at the end of the tube. An orifice 11 is provided in the end closure wall 13 for receiving the material to be sampled and lies in a plane substantially tangential to the locus of the center of the orifice. The purpose of the nose-like projection 12 is to shield the orifice 11 when the sample collecting tube 3 initially enters the stream of material, whereas the end closure wall 13 serves to arrest the particles from entering the orifice 11 during the final movement of the tube out of the stream as it will stop the im-

mediate underlying material when it is sufficiently inclined to the vertical. Thus, material will only enter the orifice during the medial portion of the arcuate movement of the sample collecting tube 3 through the stream. This occurs when the leading edge of the nose-like projection is at a higher level than the trailing edge of the orifice and the incline from the vertical of the end wall 13 is not sufficient to arrest the particles of material in the stream.

The leading edge of portion p of the orifice 11, which corresponds to the tip of the nose-like projection, and the trailing portion q of the orifice 11, are sharpened to promote a cutting action through the material when the sampling apparatus is in operation. Since it is only necessary to take an individual sample which is a few times the individual weight of the coarsest particle present in the material, the size of the orifice need only be a little greater than the coarsest particle of material to be sampled. The sharpened portions p and q of the sample receiving orifice will cut through any particles which cohere to one another.

Mounted on the shaft 1 adjacent the casing 10 is a lever arm 3 which contacts a switch 15 on the automatic timing device 4 when the sample collecting tube 3 is in the inverted position. This will stop the motor, thus stopping rotation of the shaft 1 and the sample collecting tube 3. The sample collected in the tube 3 will discharge through the discharge tube 2 into a pipe 6 which will in turn deliver the sample to a suitable receiver 7.

Since material may cling within the sample collecting tube when it is inverted, a striker or knocker 5 is provided to contact against the side of the discharge tube 2 to release clinging material through the free end thereof. The knocker 5 is mounted on an arm 5a connected to a sleeve 5b. As clearly shown in Figure 1a, sleeve 5b is freely rotatable relative to the shaft 1, and when the sample collecting tube 3 is raised upwardly, it will carry with it the knocker 5 until the knocker 5 has passed dead center of the shaft. Knocker 5 will then rotate downwardly under gravity and strike the side of the discharge tube releasing any clinging material.

Figures 2b and 3b disclose a modified form of sample collecting tube. This sample collecting tube is essentially the same as the one disclosed in Figure 2a, with the exception that the end closure plate 13c has an upwardly inclined member 13b. The inclined end member 13b is also provided with a sharpened portion q. Orifice 11, in this instance, will have a trailing edge which corresponds with the line of intersection of the planes of the end wall 13a containing the orifice and the inclined end wall 13b. In sampling wet, fine coal, a sample collecting tube provided with the angled end closure wall 13b is necessary so that during the final movement of rotation of the sample collecting tube through the material, a small amount of the material may cake on the angled end closure wall and close off the orifice to prevent material from further entering the orifice.

The operation of the device may be summarized as follows: Sample collecting tube 3 is rotated in an arcuate path on a plane inclined to the vertical through material being transferred on conveyor 9. The material will not enter the orifice 11 of the sample collecting tube 3 until the tube 3 and orifice 11 move through a vertical plane 75 through the axis of rotation, because the nose-

like projection 12 will close off and shield the orifice during the initial part of the arcuate movement through the stream of material. Once the sample collecting tube has passed through the vertical plane mentioned above, the orifice will then be opened to receive material from the center of the stream because, as previously stated, the nose-like projection will rise to a level higher than the trailing edge of the orifice. The sample received in the sample collecting and discharge tube will be transferred through the open end of the discharge tube when the sample collecting tube 3 and discharge 2 are inverted. A knocker 5 which is freely rotatable on the shaft 1 is carried by the discharge tube 2 upwardly and past the dead center of shaft 1. It will then fall by gravity and strike the side of the discharge tube 2, dislodging any material caught therein. The material picked up by the sample collecting tube 3 is transferred from the discharge tube 2 to a pipe 6 which delivers it to the sample receiver 7.

The terminology used in this specification is for the purpose of description, and not for limitation, as the scope of the invention is defined in the appended claims.

I claim:

1. A sampling apparatus for obtaining a multiplicity of small samples from the interior of a moving stream of heterogeneous material comprising in combination a sample collecting tube with an end wall having an orifice therein at one end thereof, means for rotating said sample collecting tube in an arcuate path through the stream of material, said tube having its wall adjacent the front of the orifice bulged out into a nose-like projection to prevent material entering said orifice when the sample collecting tube initially enters the stream of material.

2. A sampling apparatus for obtaining a multiplicity of small samples from the interior of a moving stream of heterogeneous material comprising in combination a sample collecting tube having side walls and an end wall, there being an orifice in said end wall for receiving the sample of material, a nose-like projection formed in the tapered side wall adjacent to said orifice, means for rotating said sample collecting tube in an arcuate path into and out of the stream of material so said projection will shield said orifice when the sample collecting tube initially enters the material, said means including a horizontal rotatable shaft, said tube being mounted on said

shaft with the longitudinal axis of said tube inclined to the vertical.

3. A sampling apparatus of claim 2 wherein leading and trailing edges of said orifice are sharpened so as to present a cutting surface.

4. A sampling apparatus for obtaining a multiplicity of small samples from the interior of a moving stream of heterogeneous material comprising in combination a rotatable horizontal shaft supported above and transverse to the stream of material, a discharge tube mounted on said shaft for rotation and having the longitudinal axis thereof inclined to the vertical, a sample collecting tube having an end wall at one end thereof detachably secured at its other end to one end of said discharge tube and in alignment therewith which will rotate in an arcuate path into and out of the stream of material, a nose-like projection formed in said sample collecting tube by bending the surface near said end wall outwardly so as to produce a local radial enlargement, and there being an orifice in said end wall adjacent to said nose-like projection for receiving the sample of material from the interior of the stream of material.

5. A sampling apparatus of claim 4 in which one edge of the orifice as defined by the nose-like projection and an edge formed by the trailing portion of said orifice are sharpened to promote a cutting action through the material tube sampled.

6. A sampling apparatus of claim 4 wherein means are provided to dislodge material clinging to the sides of said discharge tube when in an inverted position, said means including a freely rotatable knocker member mounted on said horizontal shaft, said knocker member being rotated upwardly by rotation of the discharge tube and rotated downwardly by gravity.

7. Apparatus of claim 4, wherein said end wall containing said orifice is provided with a trailing edge which is inclined to the plane of said orifice.

JAN VISMAN.
